UNITED STATES PATENT OFFICE.

LYMAN J. PECK, OF NAPA, CALIFORNIA.

ROAD-OILER.

1,279,147.

Specification of Letters Patent. Patented Sept. 17, 1918.

Application filed October 12, 1915. Serial No. 55,487.

To all whom it may concern:

Be it known that I, LYMAN J. PECK, a citizen of the United States, residing at Napa, in the county of Napa and State of California, have invented certain new and useful Improvements in Road-Oilers, of which the following is a specification.

This invention has relation to certain new and useful improvements in road oilers, and particularly to the provision in a road oiler of means for applying heated oil to the surface of a road in such manner as to properly treat the same and harden the surface.

The invention has for one of its objects the provision of a sprinkling device which will be of such construction that the quantity of oil being applied to the road surface, as well as the force with which it leaves the machine, may be readily controlled by the operator.

The invention has for a further object, the provision of a sprinkler which will be of such construction and operation that the oil will be thrown from the same in such manner as to practically separate the drops of oil, thereby assuring an even distribution of the oil over the entire surface of the road so that after several applications of oil to the road surface in this manner, the oil soaking through to the road bed will act upon the latter to harden the same, as well as the road surface and as a result prolong the life and usefulness of the road.

With the above and other objects in view the invention resides in the novel construction, combination, and arrangement of parts hereinafter set forth in the specification, pointed out in the claims, and shown in the drawings, in which—

Figure 1 is a rear elevation of the improved road oiler;

Fig. 2 is a vertical sectional view on the plane of line 2—2 of Fig. 1;

Fig. 3 is a vertical sectional view on the plane of line 3—3 of Fig. 2;

Fig. 4 is a horizontal sectional view on the plane of line 4—4 of Fig. 3;

Fig. 5 is a diagrammatic view of a portion of the invention, partly in section, showing the water coil and the connection between the same and the burner, the burner feed pipe for the same being shown in section;

Fig. 6 is a sectional view on the plane of line 6—6 of Fig. 5 with some of the feed pipes shown in plan;

Fig. 7 is a sectional view on the plane of line 7—7 of Fig. 5;

Fig. 8 is a plan of the oil coil and the pipes connected therewith;

Fig. 9 is a plan of the oil sprinkler;

Fig. 10 is a sectional view on the plane of line 10—10 of Fig. 9;

Fig. 11 is an elevation of the oil sprinkler;

Fig. 12 is a horizontal section on the plane of line 12—12 of Fig. 11; and

Fig. 13 is a perspective view of the central cup of the oil sprinkler.

Referring more particularly to the drawings in which similar reference characters designate corresponding parts throughout the several views, 1 designates the frame mounted upon suitable wheels 2 and having a large oil supply tank 3 mounted upon the same with an auxiliary or burner oil supply tank 4 to one side and the water supply tank 5 to the opposite side thereof, as clearly shown in Figs. 1 and 3 of the drawings. All of the supply tanks have suitable filling openings 6 with plugs 7 secured therein.

A suitable burner and coil inclosing casing is also mounted upon the frame 1 and preferably arranged rearwardly of the large oil supply tank 3. The casing 8 is provided with a suitable door 9 and a smoke stack 10. Leading from the large oil supply tank 3 is an oil conducting pipe 11 which extends into the casing 8 and connects with the oil heating coil 12 positioned therein above an oil burner nozzle 13, as clearly shown in Figs. 2 and 3 of the drawings. It will be understood that the oil conducting pipe 11 connects with one end of the coil 12 while a suitable T-connection 14 is secured to the opposite end or exit end of the oil heating coil 12, and has the heated oil conducting pipe 15 and the heated oil return pipe 16 leading from the same. Suitable valves 17, 18 and 19 are positioned in the pipes 11, 15, and 16, respectively, and the purpose of these pipes will presently appear.

The heated oil conducting pipe 15 connects with the supply nipple 20 mounted, as shown at 21, in the upper plate 22 of the outer casing 23 of the oil sprinkler, which will be later fully described. The heated oil return pipe 16 has connection with the large oil supply tank 3 to return the heated oil to said tank 3 from the coil 12 when the valve 19 is open and the valve 18 closed. It may now be stated that the valve 19 should

always be closed when the valve 18 is open to permit the heated oil from the coil 12 to pass to the oil sprinkler.

The oil sprinkler has a stationary bottom 5 plate 24 parallel with the upper plate 22 and said plates 22 and 24, respectively, have annular flanges 25 and 26 upon their opposed faces and provided with corresponding channels 27, within which are engaged 10 the inner ends of the guide pins 28 carried by the cylindrical body or outer casing. The stationary bottom plate 24 has a bearing sleeve 29 depending from the same and through which the rotary shaft 30 15 30 of the oil sprinkler is rotatably engaged, the bottom plate 31 of the rotary member of the oil sprinkler being mounted upon the upper end of the rotary shaft 30 and resting upon the annular flange 26 of 20 the lower stationary plate 24, as clearly shown in Fig. 10. The upper ring 32 of the rotary member of the oil sprinkler is spaced above the outer portion of the bottom plate 31 and connected with the same 25 by the curved oil throwing blades 33. Positioned inwardly of the upper ring 32 and blades 33 is a central feed cup 34 which is secured to the upper plate 22 of the outer casing by suitable securing members 35 and 30 is provided with an elongated outlet opening 36 in its side adjacent the bottom 37 of said oil feed cup 34, whereby oil may be fed from said feed cup 34 to the oil throwing blades 33 as the same rotate past the 35 oil outlet opening 36. The cylindrical body of the outer casing 23 is also provided with an elongated oil outlet slot 38 which is preferably twice as long as the oil outlet slot 36 and it will be understood that both 40 of the slots 36 and 38 are opposite the oil throwing blades 33.

Bolted to the upper plate 22 is a suitable arm 39 having an elongated slot 40 within which is engaged the pin 41 carried 45 by one end of the bell crank lever 42 which is pivoted upon the supporting standard 43 projecting upwardly from the frame 1. Pivoted to the opposite end of the bell crank lever 42 is the link 44 which is also pivoted 50 to the lever 45 carried by the larger lever 46 and adapted to be secured in adjusted position upon the same after being turned upon its pivot 47 to swing the arm 39 and thereby rotate the upper plate 22 and oil 55 feed cup 34 to the desired position to bring the oil outlet slot 36 to proper place with respect to the oil outlet slot 38 in the cylindrical body of the outer casing 23. The cylindrical body of the outer casing 60 23 also has an arm 48 secured upon its outer face and provided with an elongated slot 49 within which is engaged the pin 50 carried by a lower bell crank lever 51 which is also mounted upon the standard 43 and has 65 connected with its opposite end the link 52,

carried by the main lever 46, previously mentioned. Suitable supporting washers 53 are mounted upon the standard 43 to prevent the bell crank levers 42 and 51 from moving downwardly upon the same. It 70 will also be understood that the main lever 46 is provided with suitable locking means 54 for locking the same in adjusted position after being operated to cause the lower bell crank lever 51 to swing the arm 48 and 75 thereby turn the cylindrical body of the outer casing 23 to proper position. Upon manipulation of the levers 45 and 46, the guide pins 28 will ride in the grooves 27 during adjustment of the cylindrical body 80 of the outer casing and the upper plate 22 and oil cup 34 carried by the latter.

Within the feed nipple 20 is formed a valve seat 55, with which the valve 56 is engaged when in closed position, said valve 85 56 serving to control the passage of the oil through said feed nipple 20 and into the oil feed cup 34. The stem 57 of the valve 56 projects upwardly through the end of the connection 58 by which the oil conducting pipe 15 is connected with the feed nipple 20 and the horizontal upper end 59 of the float carrying rod 60 is adjustably secured upon the valve stem 57, as shown at 61. The float carrying rod 60 extends downwardly through the upper plate 22 and has a float 62 mounted on its lower end within the oil feed cup 34 to cause closing or opening of the valve 57 upon increase or decrease of the oil within the oil feed cup 34, as will be readily understood by referring 95 to Fig. 10 of the drawings.

The oil from the auxiliary or burner oil supply tank 4 passes to the burner nozzle 13 by way of the burner oil conducting pipe 63, 105 the end of which is secured in a mixing chamber 64, to which the burner nozzle 13 is also connected. A sleeve 65 is also secured to the end of the burner oil conducting pipe 63 by means of a reducer 66, the sleeve 65 110 being spaced from the burner oil conducting pipe 63 and connected with the steam chamber 67 which incloses one bend of the burner oil conducting pipe 63 and extends at right angles to the sleeve 65. While the steam chamber 67 may be of any construction desired, it is preferably formed of a central coupling and a pair of pipe sections connected by said coupling and having the caps 68 secured upon their outer ends. The burner oil conducting pipe 63 extends through one of the caps 68 while a steam supply pipe 69 is secured in the opposite cap 68. The steam chamber 67 is connected with the mixing chamber 64 by a suitable sectional connecting and steam conducting pipe 70. Carried by the pipe 70, within the mixing chamber 64 is a small steam discharge pipe 71 terminating within the mixing chamber 64 and directed toward the outlet thereof to 115 120 125 130

which the burner nozzle 13 is connected. The purpose of the steam discharge pipe 71 will be readily apparent as the description proceeds.

- 5 The steam supply pipe 69 leads from the top of the hot water coil 72, to the bottom of which is secured a water supply pipe 73 which leads from the main water supply pipe 74 connected with the water supply tank 10 5. A connecting pipe section 75 connects the main water supply pipe 74 with the burner oil supply pipe 63, as shown at 76 and the valve 77 within said pipe section 75 may be readily manipulated to permit the 15 proper amount of water to enter the burner oil supply tank 63 at this point and travel with the oil through the mixing chamber 64 and the burner nozzle 13 to keep the burner nozzle 13 cleared of carbon and all 20 foreign substances and assure proper operation of the device.

It will also be understood that a suitable water controlling valve 78 is positioned in the water supply pipe 73 to control the passage of water to the hot water coil 72. A short drain pipe 79 extends from the water supply pipe 73 and has a valve 80 positioned therein, whereby the hot water coil may be readily drained after closing 25 the valve 78, when desired. The steam chamber 67 also is provided with a short drain pipe 81 having a valve 82 positioned therein and which may be opened when necessary to drain the steam chamber 67 of the water condensation gathered in the same. 30

The hot water coil 72 is preferably formed of a plurality of connected curved tubes positioned parallel to one another and having their opposite ends closed by suitable caps 40 83. It will also be understood that the hot water coil 72 is positioned within the burner and coil-inclosing casing 8, at a suitable point above the burner 13 and preferably to one side of said casing 8 while the hot coil 12 is 45 positioned directly above the burner nozzle 13. It will further be understood that the mixing chamber 64 and steam chamber 67 with the parts connected directly with the same and the water coil 72, are also within 50 the casing 8, and steam from the steam chamber 67 may readily pass into and fill the sleeve 65 and reducer 66 to heat the oil passing through the portion of the oil conducting pipe 63 within said steam chamber 67, 55 sleeve 65, and reducer 66, before the oil reaches the mixing chamber 64 to be mixed with the steam passing through the same and carried by said sleeve to the mouth of the burner nozzle 13, as in the ordinary form 60 of oil burner.

From the foregoing, it will be readily seen that during operation of the device, the oil from the oil supply tank will be thoroughly heated as it passes through the oil heating coil 12 to the oil feed cup 34 of the oil

sprinkler, it being understood that the valve 18 is open while the valve 19 is closed. Rotation of the shaft 30 of the oil sprinkler will be caused by means of the drive gear 84 on the drive shaft 85 and meshing with the gear 70 86 on the rotary shaft 30 of the oil sprinkler. The oil from the oil feed cup 34 will pass through the oil outlet slot 36 thereof and will be thrown through the oil outlet slot 38 of the outer casing 23 by means of the 75 rotating blades 33. It will also be seen that the supply of oil, water, and steam to the burner nozzle 13 may be readily controlled by proper manipulation of the valves provided for this purpose. It will also be understood that the burner oil supply pipe 63 80 has a suitable valve 87 positioned therein for controlling the passage of oil through the same.

It will be understood that the levers 45 85 and 46 are preferably within reach of the operator upon the operator's seat 88. It will also be understood that the auxiliary or burner oil supply tank 4 and the water supply tank 5 are provided, respectively, 90 with valved drain pipes 89 and 90.

While the preferred embodiments of the invention have been clearly shown and described, it will be understood that minor changes in the details of construction, and 95 arrangement of parts may be resorted to within the scope of the appended claims without departing from the spirit of the invention or sacrificing any of the advantages of the same. 100

What is claimed is:—

1. A road oiler comprising a sprinkler formed of an external cylindrical member closed at the top and bottom and having an inlet for oil at the top, an inner spaced concentric cylinder forming an oil feed cup, a plurality of angularly disposed vanes between said cylinders and rotatable relatively to the same, an opening in the side of each of said cylinders for the escape of the oil, an arm projecting laterly from the side of said outer cylinder, a lever connected to said arm for oscillating the outer cylinder to change the direction of discharge of issuing oil, an outwardly extending arm 105 secured to the inner cylinder and a lever pivotally connected to the first-named lever for rocking the inner cylinder and changing the area of the oil outlet. 110

2. A road oiler comprising a sprinkler formed of an external cylindrical member, a fixed closure for the bottom of said member on which the latter is oscillatably mounted, a closure for the top of said member oscillatably mounted thereon, an oil inlet for said member opening through the top closure, an inner concentric cylinder forming an oil feed cup spaced from the external cylinder and adapted to be independently oscillatable about the common axis of the cylinders, a 115 120 125 130

- plurality of angularly disposed vanes between said cylinders and rotatable relatively to the same, an opening in the side of each of said cylinders for the outflow of oil, means for continuously rotating said vanes, and means connected to each of said cylinders for independently oscillating them for controlling the quantity and direction of outflowing oil.
10. 3. A road oiler comprising a sprinkler head formed with an external cylindrical body member, a closed bottom for said body fixed against movement on which said body is oscillatably mounted, a closed top for the body mounted thereon to oscillate independently of the body and having an inlet for oil, an inner concentric cylinder forming an oil feed cup spaced from the exterior cylinder rigidly secured to the top thereof and movable therewith, a plurality of angularly disposed vanes between said cylinders and rotatable relatively to the same, an opening in the side of each of said cylinders for the escape of oil, and operating means connected to each of said cylinders for independently oscillating them to control the quantity and direction of outflowing oil.
4. A sprinkler head for road oilers comprising a fixed bottom plate, an external cylindrical body mounted on said plate and adapted to oscillate about the axis of said body, a top for closing said body arranged to oscillate thereon independently of said body and having an oil inlet therein, an inner concentric cylinder forming an oil feed cup spaced from the external cylinder and rigidly secured to the top of the same to move therewith, a plurality of angularly disposed vanes between said cylinders and rotatable relatively to the same, an opening in the side of each of said cylinders for the es-
- cape of oil, an arm projecting laterally from the side of the outer cylinder, a second arm connected to the top of said cylinder, and a separate operating mechanism connected to each of said arms for independently oscillating the cylinders to control the quantity of oil passing from the sprinkler head and the direction of discharge of said oil.
5. A sprinkler head for road oilers comprising a bottom plate adapted to be fixed against movement, an upwardly projecting circular flange forming a part of said plate, said flange having an encircling channel in its outer edge, an external cylindrical body mounted on said bottom plate and guided by the flange thereon, pins projecting inwardly from said body into the channel of the flange to permit oscillation of the body and prevent separation thereof from said bottom, a top for closing said cylindrical body having a depending flange to enter the body formed with an external channel, pins projecting inwardly from the body into the last named channel to permit relative oscillation between the body and the top, an air inlet in said top, an inner concentric cylinder forming an oil feed cup spaced from the external cylinder and rigidly secured to said top and movable therewith, angularly disposed vanes between the cylinders and relatively rotatable to the same, an opening in the side of each of said cylinders for the escape of oil, means for continuously rotating said vanes, and means for independently oscillating the concentric cylinders.

In testimony whereof I affix my signature in presence of two witnesses.
